Filed Feb. 17, 1961, Ser. No. 90,085

5 Claims. (Cl. 339—176)

This invention relates to connectors, especially of the type to receive printed circuit boards.

The prior art contains many multiple miniature connectors which are designed to receive printed circuit boards or plugs provided with mating multiple-circuit contacts. These connectors generally have resilient metal contacts which are permanently mounted in the connector body and to which wire leads are permanently soldered.

These connectors suffer from several disadvantages: the contacts have only a single flat contact-making surface; which does not assure a good contact, especially under circumstances of severe vibration; and also have inherently a rather low removal force capability. By removal force is meant the force necessary to extract the plug from the connector. The wire leads to the contacts cannot be conveniently removed and replaced; preventing ready modification of circuitry or testing, etc. A defective contact cannot be removed from the connector body and replaced; resulting in replacement of the entire multiple contact connector.

An object of this invention is to provide a connector having contacts of novel configuration which supply several contact areas capable of making good contact, and which have inherently a very high removal force capability, all in spite of any severe vibration.

Another object of this invention is to provide a connector having contacts to which conductors may be readily connected and disconnected.

Yet another object of this invention is to provide a connector having contacts which may be readily removed and replaced.

A feature of this invention is a dielectric body having a central cavity containing a plurality of spaced-apart contact members, each having a series of reversely-bent elements, at least the innermost element having a longitudinal slit and a mediate bend.

These and other objects and features of this invention will become more apparent by reference to the following description taking in conjunction with the accompanying drawings in which:

FIG. 1A is a view in cross-sectional elevation of one embodiment of the connector of this invention and alternative plug members;

FIG. 1B is a partial cross-section view of a plug or board of the type used with this invention;

FIG. 1C is a partial cross-section view of an alternative embodiment of a plug or board of the type used with this invention;

FIG. 2a and 2b are plan and cross-sectional elevation views of the contact member illustrated in FIG. 1;

FIG. 3 is a perspective view in cross-section of another embodiment of the connector of this invention;

FIG. 4 is a perspective view in cross-section of yet another embodiment of the connector of this invention; and

FIG. 5 is a perspective view in cross-section of even another embodiment of the connector of this invention.

Referring to FIG. 1, reference character 1 indicates a body portion having a cavity 2, and an associated end cap 3, both made of dielectric material. The cap 3 may be secured to the body 1 by screws, bolts or the like (not shown). An interlocking key 4 and keyway 5, or the like, assure accurate alignment of the body and cap. Similar

spring contacts 6 and 7 are mounted in the cavity 2 in opposed relationship. Contact 6 includes a pair of reverse bends 8 and 9 forming a Z shaped compression spring, including elements 10, 11 and 12. Elements 11 and 12 are split longitudinally by a slit 6a into two sub-elements 11a, 11b and 12a, 12b, respectively. Each subelement is bent mediate, as at 13a and 13b, respectively. The free end of element 12 is bent again at 14 and 15 to provide a tab 16. The free end of element 10 is bent at 17 and formed into two cylindrical sockets 18 and 19 which are adapted to receive plugs, e.g. 20 which are connected to wires, e.g. 21. A dimple or other constriction 22 is formed into each socket to interlock with a groove 23 formed in the tip of the plug 20. The plug may be conveniently inserted and removed from the socket. The removal force required is a function of the height of the dimple.

In assembly, the spring contacts 6 and 7 are inserted into the cavity 2, tab 16 being disposed in cavity portion 24, and sockets 18 and 19 being disposed in cavity portion 25 and 26 respectively. End cap 3 is then secured to body portion 1, the orifices 27 and 28 in the cap being aligned with the cavities 27 and 28 respectively.

In use, a plug or board 40 having contact strips, as at 41 and 42 is inserted into the orifice generally indicated at 46 in the body 1, until obstructed by stop 47. Contact areas 12c, 12d, 12e and 12f of subelements 12a and 12b make a four point, resilient contact with contact strip 41 which will be maintained in good contact regardless of severe vibrational conditions. It will also be noted that as the board 40 is inserted, the contact areas 12c, 12d, 12e and 12f wipe the contact strip 41, providing a mutual cleaning of the contact surfaces. Further, contact areas 12f and 12e preclean the strip 41 for areas 12d and 12c.

Alternatively, a plug or board 43 having a profile which is similar or the mate to that of element 12, including a bulge at 44 and 45, may be inserted into the connector. In addition to the vibration-proof contact obtained by the four point resilient contact of element 12, a high removal force capability is obtained by the interlocking of bulge 44 with bends 13a and 13b.

Additionally, a polarizing key 50, which also has a profile which is the mate to that of element 12 may be inserted into the connector. The key will effectively block the contact into which it is inserted, requiring any board or plug which is subsequently inserted into the connector to have a lacuna at that contact portion.

Another embodiment of the invention is illustrated in FIG. 3, wherein body portion 301 has a bifurcated cavity 302 in which are disposed spring contacts 306 and 307 in opposed relationship. Contacts 306 and 307 have a series of elements 310, 311 and 312, and a slit 306a, which are formed and utilized in a manner similar to that of elements 10, 11 and 12, and slit 6a previously described. The free end of element 312 is bent into a tab 316 which is disposed in cavity portion 324. A cylindrical socket 318 is formed in a mediate portion of the spring contact which is adapted to receive a plug, e.g. 320, which is connected to a wire e.g. 321. A reverse bend is formed in the free end of the spring contact adjacent to the socket forming a tab 322 which interlocks with a shoulder 323 formed on the plug 320. Obviously the dimple and groove scheme previously described, or any equivalent locking scheme, could be utilized.

In assembly, the spring contacts 306 and 307 are inserted from the wire side of the connector and are locked in place by the abutment of socket face 318a against cavity face 302a and the engagement of tab 316 in cavity portion 324. Plug 320 may be inserted easily into socket 318 until tab 322 snaps behind shoulder 323, locking the plug in place. It is necessary to insert a probe to depress tab 322 when it is desired to remove plug 320.

In use, a board or plug of the type illustrated by 40 or 43 is inserted through orifice 346 into abutment with top 347, as described above.

Yet another embodiment of the invention is illustrated in FIGURE 4, wherein body portion 401 has a bifurcated cavity 402, in which are disposed spring contacts 406 and 407 in opposed relationship substantially identical to contacts 306 and 307, previously discussed. However, in this embodiment no tabs are formed on the spring contacts to secure the wire plugs. Rather, each plug, e.g. 10 20, has disposed thereon two tabs 422, which are adapted to interlock with cavity portion 423. For removal of the lug, tabs 422 may be depressed by a tweezers-type tool inserted through keyways 460 and 461.

Still another embodiment of the invention is illustrated in FIGURE 5, wherein body portion 501 has a bifurcated cavity 502 in which are disposed spring contacts 506 and 507 in opposed relationship substantially identical to elements 306 and 307 previously discussed. However, in this embodiment neither sockets nor tabs are formed on 20 25 the spring contacts to receive and retain the plugs. Rather, a return bent element 518a and 518b is formed to receive externally a socket 520. The free end of element 518a abuts the cavity wall 502a and together with tab 516 in cavity 524 (similar to cavity 24) retains 30 35 the spring contact in the body. A tab 522 is disposed in socket 520 which is adapted to interlock with cavity portion 523. For removal of the socket, tab 522 may be depressed by a probe inserted through keyway 560.

The invention has thus been described but it is desired to be understood that it is not confined to the particular forms or usages shown and described. The same being merely illustrative, and that the invention may be carried out in other ways without departing from the spirit of the invention, and therefore, the right is broadly claimed to employ all equivalent instrumentalities coming within the scope of the appendant claims, and by means of which objects of this invention are attained and new results accomplished, as it is obvious that the particular embodiments herein shown and described are only some of the many that can be employed to obtain these objects and accomplish these results.

We claim:

1. An electrical connector assembly for a printed circuit board comprising: 45
a receptacle member and a plurality of plug members; said receptacle member including a housing of dielectric material having a front and rear face, 50 a slot for receiving said printed circuit board in said front face, a plurality of spaced-apart, parallel contact-receiving bores intersecting said printed circuit board-receiving slot, 55 a plurality of openings in said rear face, at least one

associated with each of said contact-receiving bores and communicating therewith; and

a unitary contact of conductive material completely disposed in at least one of said contact-receiving bores; said contact having a rear portion for mating with one of said plug members and aligned with one of said rear face openings, a central body portion and, a front contact portion for engaging said printed circuit board, said front portion having two return bends to form a substantially Z shaped compression spring, the portion of said Z shaped spring remote from said central body portion including a longitudinal slit forming two resilient sublegs, whereby a plurality of independent contact areas are provided to engage a printed circuit board disposed through said slot, and one of said plug members being disposed through said rear face opening and contacting the rear portion of said contact,

interlocking means on said plug member and said receptacle member to resist the withdrawal of said plug member from said receptacle member.

2. A connector assembly according to claim 1 wherein each of said resilient sublegs includes at least one mediate bend on an axis transverse to said longitudinal slit to form a plurality of contact areas on each subleg.

3. A connector assembly according to claim 1 wherein the rear portion of said contact comprises a socket element having a plurality of resilient fingers having their free ends disposed with opposed edges.

4. A connector assembly according to claim 1 wherein said housing includes a shoulder adjacent said rear face and directed towards the center of said rear face opening and means upstanding from said plug member to interlock with said shoulder when said plug is inserted in the rear portion of said printed circuit contact.

5. A connector assembly according to claim 1 wherein said plug includes a peripheral discontinuity and the rear portion of said printed circuit contact includes a locking finger to cooperate with said discontinuity to lock said plug to said printed circuit contact.
